US0D1095601S

(12) United States Design Patent (10) Patent No.: US D1,095,601 S
(45) Date of Patent:  Sep. 30, 2025

(54) DISPLAY SCREEN OR PORTION THEREOF
WITH GRAPHICAL USER INTERFACE

(71) Applicant: Aristocrat Technologies Australia Pty Limited, North Ryde (AU)

(72) Inventors: Antoon Visser, Coogee (AU); Lin Liu, North Ryde (AU); Lauren Paterson, Kellyville (AU); Benjamin Tinworth, Wollstonecraft (AU)

(73) Assignee: Aristocrat Technologies Australia Pty Limited, North Ryde (AU)

() Term: 15 Years

(21) Appl. No.: 29/906,291

(22) Filed: Nov. 2, 2023

Related U.S. Application Data

(63) Continuation of application No. 29/881,793, filed on Jan. 6, 2023, now Pat. No. Des. 1,010,679, which is a continuation of application No. 29/808,901, filed on Sep. 23, 2021, now Pat. No. Des. 975,128, which is a continuation of application No. 29/795,991, filed on Jun. 22, 2021, now Pat. No. Des. 974,398, which is a continuation of application No. 29/722,813, filed on Jan. 31, 2020, now Pat. No. Des. 927,547, which is a (Continued)

(57)

CLAIM

The ornamental design for a display screen or portion thereof with graphical user interface, as shown and described.

DESCRIPTION

The FIGURE is a front view of a display screen or portion thereof with graphical user interface showing our new design.

The dashed broken line perimeter in the drawings illustrates a display screen or portion thereof and forms no part of the claimed design. The remaining dashed broken lines in the drawings illustrate portions of the graphical user interface that form no part of the claimed design.

1 Claim, 1 Drawing Sheet
